UNITED STATES PATENT OFFICE.

JOHN H. PRIDE, OF KIDDER, SOUTH DAKOTA.

BATHING-BRUSH.

1,061,566.

Specification of Letters Patent.

Patented May 13, 1913.

Application filed September 13, 1912. Serial No. 720,193.

To all whom it may concern:

Be it known that I, JOHN H. PRIDE, a citizen of the United States, residing at Kidder, in the county of Marshall and State 5 of South Dakota, have invented a new and useful Bathing-Brush, of which the following is a specification.

My invention relates to bathing brushes and the general object is to provide a bathing brush adapted for connection by a hose with an elevated water tank and which will in use deliver a flow of water through its tufts of bristles for the purpose of washing and rinsing the bather's body and also to 15 prevent soap and dirt from lodging in or about the tufts.

In the accompanying drawing Figure 1 is a top or back view of my improved bathing brush with a clamping ring on its handle in 20 diametrical section. Fig. 2 is a side view of the brush with its front end portion in section on the line *a—a* Fig. 1. Fig. 3 is a face view of a portion of the brush with the bristles removed.

Referring to the drawing by reference numerals, 1 designates the stock, 2 the handle and 3 the bristles of the brush. Inserted longitudinally of and preferably centrally through the handle is a metal tube 4, which 25 has its forward end threaded to an elbow 5, which is tightly screwed into a hole 6 through the body or stock of the brush. Either before or after the bristles are secured in the stock each tuft of them is 30 snugly inserted in an aperture 7 in a very elastic sheet of rubber 8 and the latter has its edge portion secured water-tight about the edges of the stock by a clamping band 9, which is made in two halves and hinged together at the front by a hinge 10 while the 35 rear ends of the halves are formed with segmental portions 11 almost embracing the handle, as shown in Fig. 1, but at the front of the handle may overlap as shown at 40 13 in Fig. 3, so as to hold firmly the extension 45 12 of the rubber to the handle of the brush.

14 is a ring slidable on the handle and adapted when pressed forward upon the parts 11 to hold them tightly clamped about 50 the rubber, said ring may have a shoulder 15 as shown in Fig. 2 or may be as shown in Fig. 1.

In the operation or use of the brush the rear end of the tube 4 is tightly inserted in 55 the lower end of a hose 16, whose other end

is attached to an elevated water supply (not shown) and any suitable hose clamp or other flow regulator (not shown) is placed on the hose and suitably applied for regulating the flow of water to the brush. The brush is 60 then applied to the bather's body while he is either in a bath tub or in some other place where the water may flow downward from his body. The brush is especially intended for use in bathing cabinets, an improved 65 construction of which will be found in my application of even date herewith, Serial No. 720,193.

When the bathing is done and it is desired to let the brush dry, it may be detached from 70 the hose and so placed that the water will run out of it; the ring 14 may also be slipped rearwardly, the clamp 9 spread and the rubber sufficiently opened from the brush body to let the water out quickly and 75 permit air to get into the brush and dry all its parts until the brush is to be used again, when the rubber, the clamp and the ring 14 are restored again to normal position.

It will be understood that the water passes 80 through the elbow 5 into the space 17 between the stock 1 and the rubber 8 and after spreading in said space it flows quickly out between the bristles in all the tufts. Also 85 that such flowing will be increased by the disturbance of the bristles when the brush is applied to the body. And finally that such flowing of the water cleans all soap and dirt from the brush so it will be found clean 90 when it is next time to be used. This latter 95 point of advantage is mentioned in contradistinction to fountain brushes having one single or at best perhaps a few apertures for water to come out at some point of the stock while the rest of the brush becomes clogged with soap and dirt which are very difficult to get at and remove.

What I claim is:—

A bathing brush comprising a stock with bristles at its front side, a handle on the stock, a tube longitudinally through the handle and adapted for connection with a water hose at its rear end, the front end of the tube extending through the stock to the front side of it and means for spreading the water among all the bristles before it can reach the front ends of the same, said spreading means consisting of a sheet of rubber covering the front side of the stock and having apertures embracing each one a 100

tuft of the bristles; said rubber having its edge portion brought to the edges of the stock, a clamping band fitting about the rubber and composed of two sections hinged together at the front end of the stock and having the rear ends curved so as to fit the sides of the brush handle, and a slideable

and hold the rear ends of the clamp members closed to the handle.

In testimony whereof I affix my signature, in presence of two witnesses.

JOHN H. PRIDE.
